ROOF

Ollie V. Bumpas and William G. Smith,
Memphis, Tenn.

Application December 20, 1937, Serial No. 180,809

11 Claims. (Cl. 108—17)

This invention relates to improvements in roofs made of sheet material and particularly to roofs made of sheet metal. It has particular reference to a roof made up of interlocking sheets, 5 which sheets are secured to underlying sheathing or furring strips by nails.

The primary object of the invention is to make a roofing surface which will keep all parts of the building covered thereby dry even during storms 10 or blizzards, and a roof which may be securely applied, and which when so applied and secured will protect the securing means against the elements.

Further objects are:

15 To provide a roof of interlocking sheets which are pre-formed into stock shapes, each of which sheets has one or more edges which are adapted to be secured by direct nailing to underlying furring strips or sheathing and which has its edges opposite such nailing portions shaped to interlock 20 with the nailed down edges of adjacent sheets, such nailed edges having complementary interlocks adapted to be engaged thereby; such complementary edge portions so interlocking as to 25 fully seal against the entrance of moisture and as to fully protect the nailed portions and their securing nails against exposure to moisture under any and all conditions;

To provide a roofing construction in which 30 continuous air spaces are provided between the roof surface material and the underlying roof sheathing and in which direct access of moisture to such spaces is prevented;

To provide a roofing construction in which 35 expansion and contraction is adequately provided for.

To provide a roof in which flashing or other roof portions, where conditions require, as around chimneys, vents, or flues and the like, or along 40 fire or parapet walls, are an integral part of the roofing material and are shaped and extended directly upward along such surfaces; and

To provide a roofing construction which is adapted to permit the use of various forms of 45 surface ornamentation and/or has such ornamentation.

The means by which the foregoing and other objects are accomplished and the manner of their accomplishment, will readily be understood from 50 the following specification on reference to the accompanying drawings, in which:

Fig. 1 is a front elevation of a portion of a terrace type roof showing the first two sections from the right edges of the roof with interposed gutter 55 therebetween.

Fig. 2 is a sectional elevation taken on the line II—II of Fig. 1.

Fig. 3 is a sectional elevation taken on the line III—III of Fig. 1.

Fig. 4 is a fragmentary end elevation corresponding to Fig. 2.

Fig. 5 is an enlarged detail of the locking joint shown in Fig. 3.

Fig. 6 is an enlarged cross section showing two such roof portions meeting in a valley.

Fig. 7 is an enlarged front elevation of a fragmentary portion of a terrace type roof showing a dormer type pattern thereon.

Fig. 8 is a corresponding sectional elevation taken on the line VIII—VIII of Fig. 7.

Fig. 9 is a plan view showing two intersecting valley saddles.

Fig. 10 is an end elevation of one of these saddles.

Fig. 11 is a sectional elevation taken on a line 20 similar to the line II—II of Fig. 1, showing a chimney extending through the roof, and the flashing therearound.

Fig. 11A is a sectional plan taken as on the line XIA—XIA of Fig. 11B.

Fig. 11B is a sectional elevation taken on the line XIB—XIB of Fig. 11A.

Fig. 12 is a plan view of a portion of a semi-flat roof in a Spanish tile design.

Fig. 13 is a sectional elevation taken on the line 30 XIII—XIII of Fig. 12.

Fig. 14 is a section taken on the line XIV—XIV of Fig. 12.

Referring now to the drawings in which the various parts and elements are referred to by 35 numerals, 20 is the wood sheathing of a roof; 21, 22, 23 and 24 are furring strips, the first of these 21 extending along and being flush with the lower or eave edge of the sheathing 20, the intermediate one, or ones, 22 being parallel and 40 spaced to conform to the roofing sheet size and the pair 23, 24, along the hip of the roof. Preferably all of these furring strips extend from end to end of the roof, leaving longitudinally extending air spaces therebetween, under the super- 45 posed roofing.

The roof covering comprises interlocking sheets, preferably of metal, though they may be of composition materials. The upper and lower edges of these sheets rest on a pair of the furring strips 21, 22, 23 the sheets being of inherent stiffness to span from strip to strip without undue sagging. Each of these sheets preferably comprises four rectangular tiles 31, 32, 33 and 34, with a depressed intermediate portion 55

35 forming a gutter between the first pair 31, 32, and the second pair 33, 34 of the tiles; a similar depressed portion 36 forming a gutter along one edge and a downwardly turned portion 37 along 5 the opposite edge, which downwardly turned portion of one sheet, as in Fig. 5, is shaped to interlock and seal with the gutter 36 of an adjacent sheet. As will be seen in Fig. 5, each gutter 36 has a folded lap portion 36A, adapted to overlie 10 the edge of an outwardly extending flange portion 37A of the downwardly turned edge 37; a portion 36B, continuing from the lap 36A and adapted to underlie the flange 37A, an upwardly extending portion 36C, extending upward behind the downwardly turned edge 37, a further portion 36D underlying the horizontal part 31B adjacent this edge and a further downwardly extending portion 36E, which latter portion may terminate in a further outwardly turned nailing flange 36F. 15

20 The rectangular portion 31 is joined to the rectangular portion 32, and similarly the rectangular portion 33 is joined to the rectangular portion 34, by an arcuately curved portion 38 (Fig. 2) providing a stepped or terraced effect, and the lower edges of the portions 32 and 34 terminate 25 in similarly arcuately curved portions 39, these arcuately curved portions 39 being adapted to closely embrace and interlock with complementary bead shaped edges 40, of the next underlying sheet 41. These bead shaped edges 40 have 30 continuations 42 which terminate in flanges 43, forming nailing strips which are secured to the furring strip 22, as by nails 44.

35 The starting row of sheets at each end of the roof has a flange 37C which extends downward past the sheathing 20 (Fig. 3) and may be directly nailed thereto by nails 45. Air openings 31D are formed in the flanges 37C, these openings 40 preferably being protected, as from a driving rain, by louvers 37E which may be integrally stamped outward in forming the openings.

45 The starting sheets 32A, 34A, which are used along the eaves of the roof, have the arcuate edges 39A, extended straight downward and outwardly bent to form flanges 39B adapted to seat on the furring strips 21; continuing flanges 39C are bent at right angles to the flanges 39B to cover the edges of the furring strip, and preferably also of the sheathing 20; the flanges 39C 50 being secured by nails 46. The flanges 39C, also may be bent inward, as at 39E, to underlie the sheathing 20.

55 The tiles 31, 33, which lie along the ridges of the roof are formed with arcuate beads 40A substantially identical with the arcuate beads 40; the angles however of the inwardly turned portion 42A may be sharpened up, as shown, should it be found necessary so to do to allow the nailing flange 43A to properly seat on the furring 60 strip 23.

65 The ridge of the roof is completed by a ridge cap formed in halves 50, 51, these halves being formed with arcuate flanges 52, which interlock with the beads 40A of the roof tiles, in substantially the same manner as do the edges of these tiles one with the other. The top portion of the ridge cap halves are preferably arcuate in cross section and adapted to respectively underlie and overlie each other. Preferably also the peaks of 70 these halves are provided with longitudinal crimps or corrugations 53, these corrugations being complementary and adapted to interlock to prevent leakage and sliding. The two halves are secured together as by bolts 54, which bolts 75 provide for minor adjustment and also allow as-

sembling and interlocking of the ridge with the roof sheets after those sheets have been secured in place. 55 are spacer members inserted at intervals to provide against undue closure of the corrugated interlocks. The ends of the ridge caps 5 are closed by inwardly extending plates 57, 58, respectively, which overlap. These end plates are secured together by bolts 59, slotted openings 60 in the plates allowing adjustment thereof.

In Fig. 6 a cross section is shown of a valley 10 where sheets formed as above described meet, the junction of two such valleys, and an end view of the valley alone, being shown respectively in Figs. 9 and 10. Each valley comprises a trough shaped section 65 having outwardly flanged supporting edge strips 66 along its opposite sides, these edge strips having each a reversely folded portion 67, each such portion extending inward beyond its side wall of the valley and being arcuately curved to form a bead 68 which is adapted 20 to be interlockingly engaged by arcuately curved edge portions 69 of the roof tiles. The two valleys shown in Fig. 9 are preferably stamped from a single sheet, or if not so formed are welded together along their meeting line 25 into an integral member or saddle.

70 are furring strips which are disposed parallel to the valley line at a sufficient distance apart to permit the suspending of the valley therebetween. The flanged portions 66, 67 of the 30 valley being disposed on these furring strips and secured thereto by nails 71.

It will particularly be noted in this construction, that the nails, by which the side edges and top edges of the tiles along the beads are secured 35 to the furring strips, are thereafter covered by the adjacent tiles, the edges of which tiles are interlocked with the beads to secure such edges.

75 are sheets or layers of insulating material, disposed on the sheathing 74 between the furring 40 strips 70 and the adjacent and other strips; layers of insulation are also shown in Fig. 2, and may be used with any or all of the constructions shown.

In Figs. 7 and 8, 75 are tiles each forming part 45 of a sheet as previously described, and each having a pyramidal portion 76 struck up therefrom, giving each of the tiles a dormer shaped ornamentation.

80 Figs. 11, 11A and 11B show a chimney extending through the roof, the chimney having been built so as to pass through one of the roofing tiles 81, and between the interlocking joints 82 thereof. 83 is the flashing on the upper side of the chimney, 84 that on the lower side 55 thereof, and 84A the flashing on the sides, the chimney being made smaller where the flashing surrounds it, than above the flashing, in order that a projecting portion of the chimney may overlie the upper edge of the flashing. 60 In Fig. 11 the section of the roof is taken substantially on the center line of the chimney and particular attention is called to the fact that the low point 85 of the connection from the flashing to the tile along the center line of the chimney (the section line of the view) is higher than is the connecting portions 86 in the background, at the side of the chimney, so that drainage must occur, this appearing more clearly in 70 Fig. 11B.

85 The flashing 83, 84 and 84A is formed by cutting a rectangular opening in the sheet 81, the opening being substantially of less width and length than the desired flanged opening, and 75

thereafter flanging the edges of this opening upward as shown. The flanges are subsequently cut off so that they terminate substantially in a plane, preferably roughly parallel to the surface 5 of the sheet 81.

In Figs. 12, 13 and 14 a roof is shown in which the tiles have interlocking edges substantially identical with those before shown, but different surface ornamentation, the roof illustrated being 10 of a semi-flat type. In these views 90 are substantially flat metal tiles having alternating short and long raised portions 91 and 92 respectively, both of which are substantially semi-circular in cross section, the shorter ornamentation being 15 entirely within the limits of the sheet, but the longer extending from edge to edge and interlocking with the similarly raised portions of the adjacent tiles. 93 are edge flanges which extend upward along the edge wall 94 and each are overlaid by a cap 95. On the starting tile, along the eaves, 96 is a flat edge portion which lies directly on and is secured to the sheathing 97; 98 is a downwardly flanged portion which is secured to the edge of the sheathing by nails 99. The 20 upper edge of this tile is provided with an arcuate bead 100 and a nailing flange 101, which flange is directly secured by the nails 102. The next adjacent tile has an arcuately curved lower edge 103, which interlocks with the arcuate bead 100, 25 the interlocking tile overlying and shielding the nailing flange 101 and the nails securing it. This tile is provided at its upper edge with a bead corresponding to the bead 100, with which the next tile interlocks. The tile adjacent the upper 30 edge of the roof, should that edge abut against a wall, is provided with an upwardly turned flange 104, which lies against the face of the wall 105; the top of this flange being covered by a coping 106. The tiles at their side edges have interlocking joint members 107 and a nailing flange 108 conforming to similar members 36A, 36B, etc., shown in Fig. 5; and the next adjacent interlocking members 109 similarly conforming to the members 37, 37A, etc., of Fig. 5, these interlocking members in plan lying along and parallel to the raised portions 92 of each such tile.

What we claim is:

1. A roofing surface of sheet material, comprising a plurality of interlocking rectangular sheets, and including edge and intermediate sheets, each said intermediate sheet having along an upper edge and along one side edge, continuous locking members, each said locking member having an outwardly extending edge portion adapted to be secured by nailing, and said sheet having along its respective opposite edges, interlocking members complementary respectively to said locking members, said interlocking members being adapted for interlocking with locking edges 55 of adjacent sheets and each said intermediate sheet adjacent its interlocking members to overlie and protect the nailing edges of such adjacent sheets, one or more of said sheets being apertured inwardly from said locking and interlocking members and upwardly flanged around said opening, said sheet and said flanging being integral and both continuous around said opening, the flange toward the upper edge of said sheet being connected by a sheet portion having a hip adjacent 60 the lateral center of said flange whereby drainage around said opening is effected.

2. A roofing surface of sheet material, comprising a plurality of interlocking rectangular sheets, and including edge and intermediate 65 sheets, each said intermediate sheet having along

an upper edge and along one side edge continuous locking members, each said locking member having an outwardly extending edge portion adapted to be secured by nailing, and said sheet having along its respective opposite edges, interlocking members complementary respectively to said locking members, said interlocking members being adapted for interlocking with locking edges of adjacent sheets, and each said intermediate sheet adjacent its interlocking members being adapted to overlie and protect the nailing edges of such adjacent sheets, each said sheet being laid off into individual tile patterns, said tile patterns being defined by depressed gutter portions extending from the upper to the lower edge of said sheet and having an additional gutter portion along one of its said side edges, said side edge gutter having an outer side wall extending substantially to the height of its inner side wall and forming a portion of the locking member along 10 such side edge, and said patterns being defined transversely to said gutter portions, by integral portions of said sheet conforming to the pattern of the joint between such sheet and an interlocked 15 lower adjacent sheet.

3. A roofing surface of sheet material, comprising a plurality of interlocking rectangular sheets, and including edge and intermediate sheets, each said intermediate sheet having along an upper edge and along one side edge continuous locking members, each said locking member having an outwardly extending edge portion adapted to be secured by nailing, and said sheet having along its respective opposite edges, interlocking members complementary respectively to said locking members, said interlocking members being adapted for interlocking with locking edges of adjacent sheets, and each said intermediate sheet adjacent its interlocking members being adapted to overlie and protect the nailing edges of such adjacent sheets, each said sheet being laid off into individual tile patterns, said tile patterns being defined by depressed gutter portions extending from the upper to the lower edge of said sheet and having an additional gutter portion along one of its said side edges, said side edge gutter having an outer side wall extending substantially to the height of its inner side wall and forming a portion of said locking members along 20 such side edge, said patterns being defined horizontally by integral portions of said sheet conforming to the pattern of the joint between such sheet and an interlocked lower adjacent sheet, and the contour of said gutter bottoms lengthwise thereof conforming to a parallel contour of said 25 sheet.

4. In a hip roof having sheathing abutting to form a hip; a roof covering of sheet material comprising a plurality of interlocking rectangular sheets, said sheets having interlocking side edges and continuous locking members along their upper edges, said covering being secured to said sheathing with said locking members disposed along opposite sides of said hip; and a ridge cap comprising substantially identical halves disposed in opposite relation, said halves having their lower edges shaped to interlock and seal with said sheet locking edges and their upper edges arcuately curved and longitudinally corrugated to adjustably lap and seal, and bolts securing said halves together and clamping same in interlocking relation with said sheets and with each other.

5. In a hip roof having sheathing abutting to form a hip; a roof covering of sheet material 70

comprising a plurality of interlocking rectangular sheets, said sheets having interlocking side edges and continuous locking members along their upper edges, said covering being secured 5 to said sheathing with said locking members disposed along sides of said hip; and a ridge cap comprising substantially identical halves disposed in opposed relation, said halves having their lower edges shaped to interlock and seal with 10 said sheet locking edges and their upper edges arcuately curved and longitudinally corrugated to adjustably lap and seal, and bolts securing said halves together and clamping same in interlocking relation with said sheets and with each 15 other, said halves below said arcuately curved portions, each being inwardly bent thence downwardly extended to form a belt for said bolts shielded above.

6. In a hip roof having sheathing abutting to 20 form a hip; a roof covering of sheet material comprising a plurality of interlocking rectangular sheets, said sheets having interlocking side edges and continuous locking members along their upper edges, said covering being secured 25 to said sheathing with said locking members disposed along opposite sides of said hip; and a ridge cap comprising substantially identical halves disposed in opposed relation, said halves having their lower edges shaped to interlock and seal with 30 said sheet locking edges and their upper edges arcuately curved and longitudinally corrugated to adjustably lap and seal, and said halves having integral end portions adapted to lap and form an end closure, and bolts securing 35 said halves together and clamping same in interlocking relation with said sheets and with each other.

7. A roof including a sheathing course as of 40 wood shaped in desired manner, furring strips disposed along the eave edge of said sheathing and the ridge edge thereof respectively, and intermediate furring strips disposed between said eave and ridge strips and substantially parallel to one thereof; a roof surface of sheet material 45 supported on said furring strips, said surface being of inherent stiffness to span between said strips and be supported thereby out of contact with said sheathing course, said roofing surface having at the opposite side edges of said roof 50 integrally connected downwardly turned edge portions extending substantially to the lower edge of said sheathing and secured as by nailing, said edge portions being apertured between said furring strips for entrance and exit of air, and having outwardly extending louvers overlying said 55 apertures and shielding them from the entrance of rain.

8. A roof including a sheathing course, as of 60 wood sloped in desired manner, furring strips disposed along the eave edge of said sheathing and the ridge edge thereof, respectively, and intermediate furring strips disposed between said eave and ridge strips and substantially parallel to one thereof; a roof surface of sheet material sup-

ported on said furring strips, said surface being of inherent stiffness to span between said strips and be supported thereby out of contact with said sheathing course, said roofing surface having at the opposite side edges of said roof integrally connected downwardly turned edge portions extending substantially to the lower edge of said sheathing and secured thereto, as by nailing, said edge portion being apertured between said furring strips for entrance and exit of air. 10

9. A roof construction including two adjacent sections meeting in a valley, said sections being covered by sheathing which abuts along the line of said valley; a pair of furring strips spaced apart and lying parallel with and at substantially equal distances from the center line of said valley, a substantially U-shaped trough disposed between said furring strips, said trough having side walls extending substantially vertical downward, with the bottom of said U supported by said sheathing, said trough side walls having outwardly flanged edge strips overlying and supported on said furring strips, said edge strips being folded inward and secured to said furring strips, as by nailing, the inner edges of said folded portions 20 extending beyond the side walls of said trough, and terminating each in an elongated bead extending along said channelway; and roofing surfaces of sheet material covering said sheathing, said surfaces overlying said edge strips and having their valley edges curved arcuately downward, outward, and upward to embrace and interlock with the beads of said edge strips. 30

10. A roof covering of sheet material, comprising a plurality of interlocking rectangular sheets, and including edge and intermediate sheets, each said edge sheet having along an upper edge and along one side edge, continuous locking members, and along a bottom edge a locking member complementary to said upper edge locking member, and said sheet having along its remaining side edge a downwardly extending edge member adapted to be secured by direct nailing to an edge portion as of an underlying sheathing, said latter member having ventilating openings therethrough and outwardly protruding louvers overlying said openings. 40

11. A roof including a sheathing course as of wood sloped in desired manner, furring strips disposed along the eave of said sheathing course and the ridge edge thereof, respectively, intermediate furring strips disposed between said eave and ridge strips and substantially parallel to one thereof, and sheets of insulating material disposed on said sheathing and substantially extending between said furring strips, said insulating material being of less thickness than said furring strips, and a roof surface of sheet material supported on said furring strips, said surface being of inherent stiffness to span between said strips and be supported thereby out of contact with said insulating material. 50

OLLIE V. BUMPAS.
